(57) **CLAIM**

The ornamental design for a diffuser, as shown and described.

DESCRIPTION

FIG. 1 is a perspective view of my new diffuser design, with an upper portion and a lower portion in a separated state; FIG. 2 is a front view of the upper and lower portions in a separated state;

FIG. 3 is a rear view of the upper and lower portions in a separated state;

FIG. 4 is a left side view of the upper and lower portions in a separated state;

FIG. 5 is a right side view of the upper and lower portions in a separated state;

FIG. 6 is a top view of the upper and lower portions in a separated state;

FIG. 7 is a bottom view of the upper and lower portions in a separated state; and,

FIG. 8 is a further left side view of my new diffuser design, showing the upper and lower portions in a combined state. The broken lines are for the purpose of illustrating portions of the diffuser that form no part of the claimed design.
